FINGER GUIDE FOR AN AEROSOL DISPENSER

Edward H. Green, Addison, Ill., assignor to Cleveland Aerosol Packaging Corp., Cleveland, Ohio, a corporation of Ohio

Filed May 26, 1961, Ser. No. 65,365

Term of patent 14 years

(Cl. D58—26)

Fig. 1

Fig. 2

Fig. 3

Fig. 4

Fig. 5

FIG. 1 is a top plan view of a finger guide for an aerosol dispenser embodying my new design;

FIG. 2 is a side elevational view thereof;

FIG. 3 is a front elevational view thereof;

FIG. 4 is a rear elevational view thereof; and

FIG. 5 is a bottom plan view thereof.

I claim:

The ornamental design for a finger guide for an aerosol dispenser, as shown.
